UNITED STATES PATENT OFFICE.

HARRY BOLAND, OF CHICAGO, ILLINOIS.

BACKWATER-TRAP.

1,354,879.

Specification of Letters Patent.

Patented Oct. 5, 1920.

Application filed December 30, 1919. Serial No. 348,396.

To all whom it may concern:

Be it known that I, HARRY BOLAND, a citizen of the United States, residing at Chicago, in the county of Cook and State 5 of Illinois, have invented a new and useful Backwater-Trap, of which the following is a specification.

This invention relates to improvements in back water relief valves, the principal object thereof being to provide a valve of this 10 type which acts automatically and efficiently to permit the discharge of water and sewage from the house system and the like, and to prevent water and sewage backing up 15 into the house system or the like in the event of stoppage, flood conditions, etc.

Further objects of this invention will be apparent from a consideration of the following description.

20 To the accomplishment of the foregoing and such other objects as may be hereinafter described, my invention consists in the construction, combination and arrangement of parts hereinafter described and then sought 25 to be defined in the appended claims, reference being had to the accompanying drawings forming a part hereof, and which show merely for the purpose of illustrative disclosure a preferred embodiment of my in- 30 vention, it being expressly understood that various changes may be made in practice within the scope of the claims without di- gressing from my inventive idea.

In the drawings—

35 Figure 1 is a plan view of a device constructed to embody my invention showing inlet and outlet pipes connected thereto.

Fig. 2 is a side elevation of the same, parts 40 being shown in longitudinal vertical sec- tions and in dotted lines to facilitate the disclosure.

Fig. 3 is a vertical transverse section taken substantially on line 3—3 of Fig. 2.

Referring now to the drawings, the nu- 45 meral 1 designates the casing of the valve, which is formed with the inlet extension 2 and the discharge extension 3, to which the inlet and discharge pipes or conduits 4 and 5 are respectively connected. The casing 1 is 50 substantially U-shaped in vertical cross section (see Fig. 3) and has the flat top or cover plate 6, screwed or otherwise secured to a flanged seat 7. The upper part of the chamber or compartment 8 formed within 55 the casing is provided with the relief port 9.

The inlet connection or extension 2 termi-

nates within the chamber or compartment 8 and has its end cut or otherwise formed at an incline to receive the brass seat 10 which is suitably secured thereon and has the flap 60 valve 11 pivoted thereto as at 12. This valve is extended to the other side of its pivot in the form of a float 13, adjusting weight 14 being movable on the flap valve 11 so that it is normally held in the balanced position 65 shown in Fig. 2.

A partition 15 is secured to the inside of the other wall of the casing and extends downwardly across the opening into the discharge extension 3. The upper part 16 of 70 this partition is fixed and immovable and provided with a plurality of openings or passages 17 therethrough. The lower part 18 of the partition is hinged or pivoted to the upper part at 19, but is movable in the 75 direction of discharge flow only, having stops or abutments 20 for limiting its move- ment in the other direction. It is to be noted that this lower movable part of the partition is shaped to fit the casing but is 80 smaller in dimension so as to leave a space 21 around its edge. The partition 15, hav- ing the openings 17 and the hinged flap 18, are for the purpose of controlling the back water. When the back water flow sets in, 85 the hinged part 18 will close, preventing the backing up of any solid matter, the openings 17 permitting the flow of water into the chamber or compartment 8 on to the flap valve 11, so as to force the same to its seat 90 and prevent the rise of the back water into the system.

The operation of this device is obvious. Under normal condition, the water and sewage will readily flow through from inlet 95 to discharge but where there is a stoppage or the level of the water in the discharge system is raised sufficiently to cause back water as in flood conditions, the movable part 18 of the partition is held closed in its 100 full line position in the drawing and the pressure and flow of the back water through the openings 17 of the upper part thereof, forces the flap valve 11 shut against its seat, thereby holding the same closed until the 105 condition is relieved and preventing the water, etc., from backing up into the house system or the like.

What I claim is:—

1. A device of the character described in- 110 cluding in combination a casing having an inlet connection and an outlet connection, a

valve seat for said inlet connection and a balanced valve for said seat, a partition extending across the casing adjacent the outlet connection, part of said partition being movable in the direction of discharge flow only.

2. A device of the character described including in combination a casing having an inlet connection and an outlet connection, a 10 valve seat for said inlet connection and a balanced valve for said seat, a partition extending across the casing adjacent the outlet connection, the lower part of said partition being movable in the direction of discharge flow only, and the upper part of said 15 partition being provided with openings therethrough.

3. A device of the character described including in combination a casing having an inlet connection in the lower part thereof, a 20 valve having a float extension and pivoted so as to swing to close said inlet connection, said valve being normally open, said casing having an outlet connection, a partition extending across the casing adjacent the outlet connection, the upper part of said partition being stationary and provided with openings therethrough and the lower part of said partition being hinged to said stationary part, and abutments on said casing for 25 preventing the movement of said hinged part of said partition in the direction of inflow.

HARRY BOLAND.
